UNITED STATES PATENT OFFICE.

ROBERT L. DENNISON, OF KANSAS CITY, MISSOURI.

DEEP-WELL PUMP.

Application filed January 20, 1927. Serial No. 162,354.

This invention relates to deep well pumps of the impeller type.

As is well known, it has been proposed to provide deep well pumps wherein a drive shaft is mounted axially within the well tubing and provided at spaced intervals with impellers, such as those of the screw type. Such pumps have been found to work satisfactorily but are inefficient due to losses resulting from the inherent characteristics of the impellers. With pumps of this type, the rotation of the shaft is transmitted to the fluid being pumped in two directions, namely upwardly, and outwardly due to centrifugal force. The propellers of the screw type usually employed in pumps of this character operate within smooth bores which offer no assistance to the pump in effecting an upward movement of the fluid, and the centrifugal force thus exerted is wholly lost, thus rendering the pumps inefficient.

An important object of the present invention is to provide a pump of the character outlined having means for increasing its efficiency whereby a greater volume of liquid may be pumped with the same power application.

A further object is to provide a pump of the character referred to having means adapted to utilize the centrifugal force for assisting in the lifting action, thus increasing the efficiency of the pump.

A further object is to provide a pump employing a drive shaft having screw impellers mounted therein at spaced intervals and provided with peripheral bands having spiral inwardly extending ribs which are adapted to assist in the lifting action of the pump as the impellers are rotated.

A further object is to provide a pump of the above mentioned character having means arranged adjacent each of the impellers for overcoming the swirling action of the water to permit the adjacent impeller more efficiently to act upon the liquid.

Other objects and advantages of the invention will become apparent during the course of the following description.

In the drawings I have shown one embodiment of the invention. In this showing:

Figure 1 is a central vertical sectional view through a portion of the apparatus,

Figure 2 is a section on line 2--2 of Figure 1,

Figure 3 is a similar view on line 3--3 of Figure 1, and,

Figure 4 is a detail section through one of the impellers.

Referring to the drawings the numeral 10 designates a plurality of well tube sections arranged in axial alinement. The upper end 55 of each section is externally threaded for reception within the internally threaded lower end of a coupling member 11, the internal diameter of which is preferably equal to the internal diameter of the tube sections. Each coupling 11 is provided with a hub 12 having a bearing bushing 13 therein to rotatably receive a drive shaft 14, this shaft preferably being made up of a plurality of sections 15, as clearly shown in Figure 1. Each coupling 60 11 also is provided with a plurality of preferably integral radial fins 16 for a purpose to be described.

The upper end of each coupling 11 is externally threaded for reception within the 75 lower internally threaded end of another coupling member 17, the latter having an enlarged lower end 18 provided with the internal threads. The upper end of each coupling 17 is internally threaded to receive 80 the externally threaded lower end of the next adjacent tube section 10.

An impeller indicated as a whole by the numeral 19 is arranged in each coupling 17. Each of the impellers is provided with a hub 85 20, and the ends of the shaft sections are preferably threaded in this hub whereby the latter serves as a coupling member for the shaft sections. Each impeller further includes a surrounding band 21 which is rotatable within the corresponding coupling 17, and the internal diameter of the band 21 is preferably equal to the internal diameters of the tube sections and the coupling 11. Spiral blades 22 are carried by each impeller and 90 are preferably formed integral therewith. In the form of the invention shown, each impeller is illustrated as being provided with two diametrically opposite blades. Between the blades 22, the band 21 is provided with a 95 plurality of inwardly extending preferably integral ribs 23 which are spirally arranged and correspond to the pitch of the blades 22.

The operation of the device is as follows:

The shaft 15 is driven at a relatively high 100 speed in the usual manner to rotate the im-

ellers, and the blades of the latter are adapted to effect an upward movement of the liquid being pumped. This rotating movement is transmitted to the liquid in two directions, namely, upwardly, and outwardly radially of the shaft. Ordinarily, the radial forces are completely lost and the pumping action effected is the result only of the upward force exerted by the impellers. It has been found that the provision of the ribs 23 serves to transform the radial movement into an upward movement since the liquid is not permitted to lie against the smooth surrounding wall and to slip thereagainst. Attention is invited to the fact that the inner surfaces of the bands 21 form substantial continuations of the surfaces of the tube sections and the coupling 11, thus minimizing frictional resistance to the movement of the liquid. This action also is assisted by virtue of the fact that the diameters of the hubs 12 and 20 are equal. The fins 16 serve to straighten the direction of travel of the liquid to eliminate the swirling action thereof, as the liquid approaches the next higher impeller, thus assisting in minimizing the swirling action again delivered to the liquid by the successive impellers.

It will be obvious that the apparatus is adapted to be readily assembled by virtue of its sectional construction as illustrated in Figure 1. Each successive shaft section is placed in position and the shaft section is connected to the hub of one of the impellers, whereupon the next coupling 17 and tube section 10 is placed in position. It also will be apparent that the device readily may be disassembled for the purpose of making repairs.

By virtue of the increased efficiency provided by the pumping action, it has been found that the apparatus is particularly adapted for use as a deep well pump.

It is to be understood that the form of the invention herewith shown and described is to be taken as a preferred example of the same and that various changes in the shape, size and arrangement of parts may be resorted to without departing from the spirit of the invention or the scope of the subjoined claims.

I claim:

1. Apparatus of the character described comprising a well tubing, a rotatable shaft mounted axially within said tubing, an impeller carried by said shaft, said impeller including a pitched blade, a sleeve surrounding the blade and rotatable therewith, and means carried by and projecting inwardly from said sleeve for minimizing circumferential slippage of fluid against the interior of said sleeve.

2. Apparatus of the character described comprising a well tubing, a rotatable shaft mounted axially within said tubing, an impeller carried by said shaft, said impeller in-

cluding a hub, a pitched blade carried by said hub, a sleeve surrounding said blade and rotatable therewith, and an inwardly projecting rib formed on the inner surface of said sleeve and pitched similarly to said blade. 70

3. Apparatus of the character described comprising a well tubing formed of a pair of alined sections, a coupling connecting the adjacent ends of said sections and having an internal diameter larger than the internal diameter of said sections, a rotatable shaft mounted axially within said tubing, a hub carried by said shaft within said coupling, a pitched blade carried by said hub, a sleeve surrounding said blade and rotatable therewith, said sleeve having its outer face substantially contacting with said coupling and having an internal diameter substantially equal to the internal diameter of said tubing sections, and means carried by and projecting inwardly from said sleeve for minimizing circumferential slippage of fluid against the inner surface of said sleeve. 80 85

4. Apparatus of the character described comprising a well tubing formed of a pair of alined sections, a coupling connecting the adjacent ends of said sections and having an internal diameter slightly larger than the internal diameter of said sections, a rotatable shaft mounted axially within said tubing, a hub carried by said shaft within said coupling, a pitched blade carried by said hub, a sleeve surrounding said blade and rotatable therein, said sleeve having its outer face substantially contacting with said coupling and having an internal diameter substantially equal to the internal diameter of said tubing sections, and a rib formed integral with said sleeve and projecting inwardly therefrom, said rib being pitched similarly to said blade. 90 95 100 105

5. Apparatus of the character described comprising a well tubing formed of upper and lower alined sections, a coupling arranged on the upper end of the lower section and having an internal diameter substantially equal to the internal diameter of said sections, an axial bearing carried by said coupling, a shaft rotatable in said bearing, an upper coupling connecting the upper end of said first named coupling with the lower end of the upper tubing section, said upper coupling having an internal diameter larger than the internal diameter of said sections, a hub carried by said shaft within said upper coupling, a plurality of pitched blades carried by said hub, a sleeve rotatable in said upper coupling and connected to the outer edges of said blades, and means carried by and projecting inwardly from said sleeve for minimizing circumferential slippage of fluid within said sleeve. 110 115 120 125

6. Apparatus of the character described comprising a well tubing formed of upper and lower alined sections, a coupling arranged on the upper end of the lower section 130

- and having an internal diameter substantially equal to the internal diameter of said sections, an axial bearing carried by said coupling, a shaft rotatable in said bearing, an upper coupling connecting the upper end of said first named coupling with the lower end of the upper tubing section, said upper coupling having an internal diameter larger than the internal diameter of said sections, a hub 10 carried by said shaft within said upper coupling, a plurality of pitched blades carried by said hub, a sleeve rotatable in said upper coupling and connected to the outer edges of said blades, and a plurality of ribs formed integral with said sleeve and projecting inwardly from the inner face thereof, said ribs being spaced from said blades and pitched similarly thereto.
7. Apparatus of the character described 20 comprising a well tubing formed of upper and lower alined sections, a coupling arranged on the upper end of the lower section and having an internal diameter substantially equal to the internal diameter of said sections, an axial bearing carried by said coupling, a shaft rotatable in said bearing, an upper coupling connecting the upper end of said first named coupling with the lower end of the upper tubing section, said upper coupling having an internal diameter larger than the internal diameter of said sections, a hub carried by said shaft within said upper coupling, a plurality of pitched blades carried by said hub, a sleeve rotatable in said upper coupling and connected to the outer edges of said blades, a plurality of ribs formed integral 30 with said sleeve and projecting inwardly from the inner face thereof, said ribs being spaced from said blades and pitched similarly thereto, and a plurality of longitudinally extending fins formed integral with and connected between said bearing and said first named coupling.
8. Apparatus of the character described 40 comprising a well tubing formed of upper and lower alined sections, a coupling arranged on the upper end of the lower section and having an internal diameter substantially equal to the internal diameter of said sections, an axial bearing carried by said coupling, a shaft rotatable in said bearing, an upper coupling 45 connecting the upper end of said first named coupling with the lower end of the upper tubing section, said upper coupling having an internal diameter larger than the internal diameter of said sections, a hub carried by said shaft within said upper coupling, a plurality of pitched blades carried by said hub, a sleeve rotatable in said upper coupling and connected to the outer edges of said blades, a plurality of ribs formed integral 50 with said sleeve and projecting inwardly from the inner face thereof, said ribs being spaced from said blades and pitched similarly thereto, and a plurality of longitudinally extending fins formed integral with and connected between said bearing and said first named coupling.
